[57] CLAIM

The ornamental design for a hinged purse, substantially as shown and described.

DESCRIPTION

FIG. 1 is a front elevational view of a hinged purse showing my new design in a closed position;

FIG. 2 is a rear elevational view thereof;

FIG. 3 is a top plan view thereof;

FIG. 4 is a bottom plan view thereof;

FIG. 5 is a right side elevational view thereof; the left side elevational view is a mirror image of the right side elevational view shown;

FIG. 6 is a front elevational view of the hinged purse in an open position; and

FIG. 7 is a right side elevational view of FIG. 6.

FIG. 1.

FIG. 2.

FIG. 3.

FIG. 4.

FIG. 5.

FIG. 7

FIG. 6.
